UNITED STATES PATENT OFFICE.

ALEXANDER WINTON, OF LAKWOOD, OHIO, ASSIGNOR TO THE WINTON GAS ENGINE & MANUFACTURING COMPANY, OF CLEVELAND, OHIO, A CORPORATION OF OHIO.

INTERNAL-COMBUSTION MOTOR.

1,321,693.

Specification of Letters Patent.

Patented Nov. 11, 1919.

Application filed November 20, 1914. Serial No. 873,210.

To all whom it may concern:

Be it known that I, ALEXANDER WINTON, a citizen of the United States, residing at Lakewood, in the county of Cuyahoga and State of Ohio, have invented certain new and useful Improvements in Internal-Combustion Motors, of which the following is a specification.

This invention relates generally to improvements in internal combustion motors and particularly to mechanism for feeding fuel to internal combustion motors of the high compression type.

More specifically the invention relates to fuel feeding mechanism for multiple cylinder high compression internal combustion motors, and it comprises a plurality of fuel pumps, each having an independent governing valve, and an additional valve for positively varying the supply to the governor.

The invention may be further briefly summarized as consisting in the construction and combination of parts hereinafter set forth in the following description, drawings and claims.

Referring to the drawings, Figure 1 is a side elevation of an engine of the type utilizing this device; Fig. 2 is a front elevation partly in section showing the fuel feeding device; Fig. 3 is a sectional view; Fig. 4 is a bottom plan view; Fig. 5 is a detail view of a form of governor which may be used with the device; Fig. 6 is a sectional view of the type of primary fuel and air mixing valve utilized with the device and Fig. 7 is a detail view of the clamping screw of the governor hand lever.

In carrying out the invention any preferred form and construction of engine and parts may be employed, but I have shown one arrangement which is effective, and in such embodiment 1 represents a suitable crank case having mounted on it a plurality of cylinders 2 each of which is provided with suitable exhaust manifold and valve mechanism and suitable air inlet mechanism for the auxiliary air supplied to the engine, the details of these features being of no particular importance. Each of the cylinders is also provided, preferably at its head, with a suitable primary fuel and air mixing valve structure, and this structure consists of a casing 3 having a centrally disposed mixing opening 4 terminating at the lower end in a valve seat 5 within the cylinder. A

suitable guiding flange 6 projects into the opening 4 and serves to guide a valve stem 7 having suitable longitudinal openings 8 adjacent to the flange to permit the passage of the mixture of air and fuel. Near the upper end of the casing 3 and outside of the cylinder is a connection 9 connected by a port 10 with a longitudinally disposed port 11 which communicates by a port 12 with the opening 4. These ports serve to supply the fuel. The casing 3 is also provided outside of the cylinder with a connection 13 provided with a port 14 extending directly into the opening 4 and arranged to supply air under pressure at a point removed from the fuel inlet. The valve 7 is provided immediately above the flange 6 with a plurality of washers 15 having lugs 16 and varying alternately in their inner and outer peripheral dimensions so as to produce a circuitous passage for the mixture of air and fuel in effecting the mixture. These washers extend to a point near the port 12, and from this point to the upper end of the casing the stem is provided with a sleeve 17 less in diameter than the bore of the opening 4 to a point near the top of the port 14 so as to permit the passage of the air downward to the mixing portion of the valve mechanism. The upper end of this sleeve is enlarged at 18 to fit the bore of the casing, and provided with a suitable gland portion 19 co-operating with a stuffing box structure applied to the upper end of the casing.

The engine is also provided with a suitable governor, preferably of the type shown, and comprising a vertical shaft 20 supported in a suitable casing 21 forming a part of the engine. The shaft 20 is driven by the engine in any suitable manner and extends well above the upper end of the casing 21, where it is provided with a hub 22 keyed to the shaft by a suitable key 23 and having a laterally extending flange 24 forming the bottom of the governor casing. This hub 22 extends loosely through an opening in the upper end of the casing 21 and rotates therein. The hub is provided with an annular recess or depression 25 for receiving an opening 25' for a purpose to be described. The flange 24 rests upon a thrust bearing race 26 engaging thrust bearing balls 27 which in turn engage another race 28 arranged upon the upper end of the casing 21. This thrust bearing supports 110

the governor mechanism and also takes the thrust of the springs therein, as will later appear. The flange 24, which forms the bottom of the governor casing, is provided 5 with diametrically opposed upwardly extending ears 29, in the upper end of each of which is pivoted a governor ball lever 30 having a friction roller 31 in one end engaging in an annular recess 32 formed in a 10 sleeve 33 loosely mounted upon the shaft 20 and a governor ball 30' at the other. This sleeve extends upward and is provided with an annular groove 34 upon the outside to receive the yoke of a governor lever 35 pivoted upon a pin 36 secured to a stationary part. The opening in the sleeve 33 is enlarged to form an annular opening 37 around the shaft 20 in which is arranged a coil spring 38, this spring bearing against a 15 shoulder 39 formed within the sleeve and against a thrust sleeve 40 slidably mounted upon the shaft 20. The upper end of the sleeve 40 engages a thrust bearing structure 41 arranged between it and a shouldered 20 control lever collar 42, this collar being loose upon the shaft 20. The shoulder of this collar is adapted to be engaged by a lever arm 43 pivoted upon a shaft 44 secured in a bracket 45 mounted upon the engine. This shaft 44 is operated by a hand 25 lever 46 provided with a concentric slot 47 adapted to receive a pin 48 carried by a bracket 49 secured to the bracket 45. The bracket 45 is provided with a bearing 50 engaging the upper end of the shaft 20. The pin 48 is threaded on its outer end and is provided with a clamping hand screw 51 adapted to clamp the hand lever 46 in any 30 adjusted position. The governor balls, and the mechanism thereabout, is incased in a suitable casing 52 supported by a flange 53 engaging the flange 24. The governor lever 35 is connected, as will later appear, to the fuel feeding mechanism.

45 The fuel feeding mechanism will now be described. Mounted in some convenient place on the engine is a housing 54 provided with an eccentric shaft 55, shown in dotted lines in Fig. 2 and in full lines in 35 Fig. 3, and this shaft is provided throughout its length with a plurality of eccentrics 56, one for each cylinder, and each of these eccentrics engages within an eccentric strap 57 having ears 58. The shaft 55 is also provided within the housing with a gear 59 engaging a driving gear 60 mounted upon a cam shaft 61 supported by the engine and driven from any rotating part. The ear 58 of each of the eccentric straps is provided 40 with a pin 62 passing through an eye 63 arranged in the upper end of a pump plunger 64 which passes through a suitable stuffing box structure 65 into a pump barrel 66 preferably formed in the housing. Each of 45 these pump barrels is in direct communica-

cation with a horizontal port 67 in turn communicating with a discharge port 68 leading to a check valve structure 69 arranged in the housing. This check valve structure communicates with a check valve 70 structure 70 in a block 71 and a like structure in a block 72 which in turn is in communication with a discharge block 73 provided with an outlet 74. These blocks are held in place by suitable cap screws 75. The 75 port 67 is also in communication with a governor block 76 having therein a check valve structure 77 communicating with a governor valve chamber 78 which is provided with a valve seat 79 arranged between 80 this chamber 78 and the supply port 80 in the block 76. Slidably mounted within the block is a governor valve stem 81 having a tapered valve 82 at its end coöperating with the seat 79. A suitable stuffing box 85 structure 83 is arranged about this valve stem to prevent leakage at this point. Communicating with the inlet opening 80 is an opening 84 arranged in an inlet check valve 86. This opening 84 communicates with a 90 check valve opening 87 in an individual control block 88, this opening communicating by means of a valve seat 89 with a general supply port 90. This valve seat is adapted to be engaged by a needle valve 91 having 95 a threaded shank 92 engaging in the individual control block 88. A suitable stuffing box structure 93 is arranged about this stem and the end of the stem is provided with a hand wheel 94. All of these inlet 100 parts are secured to the housing by means of cap screws 95. There is a complete discharge check valve structure and inlet structure including the governor valve and the individual control valve for each of the 105 cylinders and for each of the eccentrics, and the governor valves are controlled as a gang, as will now be described.

Each of the governor valves 81 is threaded at 96 through a bar 97 and held in 110 any adjusted position in said bar by means of check nuts 98 and 99. This bar 97 is provided with trunnions 100 at each end, as shown in Fig. 2, and each of these trunnions engages in a bearing 101 formed on the end of an arm 102, the other end of the arm having a bearing 103 engaging an eccentric forming a part of the shaft 105 supported in bearing 106 secured to the rear of the block 76. This shaft 105 is adapted to 115 be rocked by a crank arm 107 connected to a link 108 in turn pivotally connected to the governor lever 35 of the governor.

Assuming that the engine is at rest, and that the operator has previously moved the 125 hand lever 46 to the left, releasing the spring 38, so that the spring 25' is free to raise the sleeve 33 and throw the governor balls outward, then to start the engine the hand lever 46 is grasped and tension 130

brought to bear upon the spring 38, thus moving the governor into starting position, with the result that the governing valves have been moved outward to the proper 5 point of starting. The starting mechanism, not shown, for the engine is then set in operation, and rotation is set up. As soon as the engine is operating under its own power, when the fuel pumps will be throwing the 10 proper amount of fuel, controlled by the governing valves and the hand valves, the governor then regulates this control and serves to supply the proper amount of fuel to each cylinder. It is obvious that the 15 control of each governing valve may be adjusted and that each individual supply to the governing valve may be adjusted through the hand operated valves 91.

Having described my invention, I claim:—
20 1. Fuel pump mechanism for internal combustion motors comprising a plurality of fuel pumps, a discharge for each pump, an inlet for each pump, an inlet valve, a governing valve for each pump, a bar connecting all of said governing valves, means 25 for adjusting each valve in said bar, and mechanism for moving said bar.

2. Fuel pump mechanism for internal combustion motors comprising a plurality of fuel pumps, a discharge for each pump, 30 an inlet for each pump, an inlet valve, a governing valve for each pump, a bar for connecting all of said governing valves, means for adjusting each valve in said bar, and mechanism for moving said bar, comprising a shaft rotatably mounted, eccentric members carried by said shaft, links connecting said eccentrics and said bar, and means for actuating said shaft. 35

3. In combination with an internal combustion motor, a governor, a series of fuel feeding pumps for the cylinders of said motor, a series of valves connected in a gang and operated by said governor as a unit for regulating the fuel fed to said pumps in accordance with the speed, and additional means for individually adjusting the fuel supply to each pump. 40 45

In testimony whereof I affix my signature in presence of two witnesses.

ALEXANDER WINTON.
